UNITED STATES PATENT OFFICE.

JESSIE MAY SLINGER, OF RIVERSIDE, CALIFORNIA.

DESIGN FOR A FLOWER STAND.

Application filed September 15, 1921. Serial No. 500,971. Term of patent 3½ years.

To all whom it may concern:

Be it known that I, JESSIE MAY SLINGER, stand, showing my new design. a citizen of the United States, residing at Riverside, county of Riverside, State of California, have invented a new, original, and ornamental Design for Flower Stands, of which the following is a specification, reference being had to the accompanying drawing, forming part thereof.

The figure is a perspective view of a stand, showing my new design.

I claim:

The ornamental design for a flower stand as shown.

JESSIE MAY SLINGER.
